UNITED STATES PATENT OFFICE

117,382

DESIGN FOR A BOTTLE

Ovid S. Parker, South Gate, Calif., assignor to De La Salle Institute, a corporation of California, doing business as Christian Brothers, Napa, Calif.

Application August 22, 1939, Serial No. 86,833

Term of patent 14 years

To all whom it may concern:

Be it known that I, Ovid S. Parker, a citizen of the United States, residing at South Gate, in the county of Los Angeles and State of California,
have invented a new, original, and ornamental Design for Bottles, of which the following is a specification, reference being had therein to the accompanying drawing, forming a part thereof.

Fig. 1 is a side elevational view of a bottle showing my new design.

Fig. 2 is a similar view of the opposite side
thereof.

I claim:

The ornamental design for a bottle, as shown.

OVID S. PARKER.
